ness under the name and style of Goldwyn
Brothers

Original application November 24, 1937, Serial No.
176,212. Divided and this application April 16,
1938, Serial No. 202,416

1 Claim. (Cl. 112—256)

This invention relates to improvements in sewing machines and it consists of the matters hereinafter described and more particularly pointed out in the appended claim. The present application is a divisional one, the subject matter herein having first been presented in our copending application filed November 24, 1937 and bearing Serial Number 176,212.

The invention is more particularly concerned with power driven industrial sewing machines adapted for darning and mending fabrics and wherein one or more needle threads are used. In darning or mending fabrics such as used burlap bags, the fabric operated upon is manually moved back and forth and laterally in both directions without any particular regularity of movement until the stitches are interwoven to that degree which either closes the hole in the fabric or reinforces the worn place therein. As no regularity of forward feed is necessary in a sewing machine of this kind, it is devoid of the conventional or other type of feed dog.

In operating upon fabric such as used burlap bags for darning or mending, a considerable amount of dust, lint and foreign particles is dislodged from the bag and in sewing machines as heretofore were available for this purpose, such dust, lint and foreign particles easily found entrance to the internal mechanism thereof. In some instances said particles might be of an abrasive character so that wear quickly develops in the rapidly moving parts of said mechanism. Also dust and lint particles combined with the lubricant to form a hard paste-like substance having substantially no lubricating value. This substance not only hastens wear, but slows down operating speed and necessitates frequent lubrication by hand as well as stops for servicing.

One of the objects of the present invention is to provide a sewing machine of the type for darning and mending fabrics wherein all moving parts for reciprocating the needle bar and for oscillating the shuttle are enclosed against the entrance of dust, lint and foreign particles produced in operation and are lubricated by a circulation of clean oil so that wear on said moving parts is reduced to a minimum.

Another object of the present invention is to provide a lubricating system for sewing machines of this kind which is of a combined character in that it is partly force feed, partly gravity feed and partly splash feed.

The above mentioned objects of the invention as well as others, together with the advantages

thereof will more fully appear as the specification proceeds.

In the drawings:

Fig. 1 is a longitudinal vertical sectional view through the operative parts of a sewing machine embodying one form of the invention, certain portions appearing in side elevation for a better illustration thereof.

Fig. 2 is a top plan view of the base of the machine with parts appearing as broken away better to disclose the invention.

Fig. 3 is a top plan detail view of the head end of the overhanging arm of the machine and which will be more fully referred to later.

Fig. 4 is a transverse vertical detail sectional view through a part of the mechanism of the sewing machine on a somewhat enlarged scale as taken on the line 4—4 of Fig. 1.

Referring now in detail to that embodiment of the invention illustrated in the drawings, 20 indicates as a whole the base of the sewing machine head upon which is mounted a hollow arm indicated as a whole as at 21.

The base is made as a one-piece casting comprising a hollow rectangular body 22 on the longitudinal median line of which is a hollow extension 23 having a wall 24 at its outer end formed with laterally spaced shuttle race holding extensions 25—25. The top of the base is made flat to provide a bed plate 26 for the sewing machine head as a whole of a width from front to rear approximating that of the body 22, a part of said base plate being formed as a laterally extending flange 27 on the top side of the hollow extension. In the bottom of the body is an opening 28, closed by a cover plate 29 and in the top side of the body is an opening 30, the purpose of which will soon appear. Depending from the top side of the body just forward of the opening 30 is a bearing boss 31. An oscillating rock shaft 32 is journaled near its inner end in said boss and is journaled near its outer end in the wall 24. An oil retainer 35 is provided in said wall to prevent leakage at this point of the lubricating oil with which the base is filled up to about the axis of the shaft 32.

The arm 21 includes a substantially upright hollow standard 36 and a horizontally disposed hollow extension 37 that terminates at its free end in a hollow head 38. The open end of said head is closed by a cover plate 39. The bottom end of the standard is suitably faced off for an oil-tight fit on the top surface of the body 22 of the base, the interior of the arm 21 as a whole

communicating with the interior of the base through the opening 30 before mentioned. In the hollow extension 31 are provided inner end, intermediate and outer end bearing bosses 40—41 and 42 respectively, in which a rotatable main driving shaft 43 is suitably journaled.

5 The main driving shaft 43 is provided at a point between the bearing bosses 40—41 with a crank 44 with which the top end of a connecting rod 45 is operatively connected. The bottom end of said rod is operatively connected to a rock arm 46 arranged in the hollow body of the base and mounted on a hinge pin 47 that bears at one end in the boss 31 and that bears at its other end in 10 an upright end wall 48 of the body 22. The rock arm 46 is operatively connected to the shaft 32 through suitable conventional mechanism indicated as a whole as at 49. This mechanism includes a block 50^a pivoted on an arm 50 on the 15 inner end of the rock shaft 32 and which block slides in a bifurcation 46^a in the arm 46 as appears in Fig. 4, whereby rocking movement of the arm 46 operates to impart a rocking movement to the shaft 32.

25 An eccentric 51 is carried by the arm 46 at a point between the connecting rod 45 and the end wall 48 of the base body. This eccentric is disposed above an upright pump plunger 52 arranged in a cylinder 53 formed in the end wall 48 30 of the base body. The bottom end of said plunger normally engages upon a spring 54 in said cylinder and which spring exerts an upward pressure on the plunger. A port 55 formed in the wall 48 provides the inlet for the cylinder and a passage 35 56 in said wall, that is closed at its outer end, provides the discharge side or outlet for said cylinder. A spring pressed check valve 57 is provided in said outlet passage for the pump. The mechanism just above described best appears in 40 Fig. 1.

In the rocking of the arm 46 and its eccentric 51, the plunger 52 is reciprocated vertically, the eccentric providing the downward movement of the plunger and the spring 54 providing the upward movement therefor. When the bottom end of the plunger clears the port 55 in the upward movement of the plunger, oil passes through the port 55 into the cylinder. In the downward movement of the plunger, when its bottom end 45 passes the port, it closes the same and imposes a pressure on the oil in the cylinder so that oil is forced out through the passage 56 for distribution as will later appear, the check valve 57 operating to close said passage on the suction stroke 50 of the plunger.

55 60 indicates a balance wheel fixed to an extension 43^a of the main shaft 43 outwardly of the bearing boss 40 therefor and which wheel is provided with a friction face 62. A pulley 63 is journaled on the extension 43^a outwardly of the balance wheel and is provided with the usual groove 64 to receive a belt (not shown) whereby the pulley is driven from a suitable source of power. When the pulley is moved toward the balance 65 wheel, it frictionally grips the facing 62 so as to drive the balance wheel and the shaft 43 to which it is secured.

The pulley 63 is normally held out of driving engagement with the fly wheel by means of a 70 spring 65 arranged axially of the shaft extension and between the extremity of said extension and a cap 66 carried by the pulley. This cap carries a thrust receiving member 67 in the form of a ball confined in the cap in line with the axis of the shaft extension.

To impart a thrust to the pulley to operatively engage it in driving relation with the balance wheel, the following construction is provided: 70 indicates an upstanding lever arranged at the right hand end of the base 20 and arm 21 respectively and pivoted at a point 71 between its ends on the standard 36. This lever includes an arm 72 that depends below the pivot 71 and an arm 73 that projects above said pivot. The free end of the arm 73 carries a thrust imposing member 10 74 for engagement with the thrust receiving member 67 of the pulley. The member 74 constitutes a screw threaded into the arm and secured in place by an associated nut. By this arrangement the parts may be adjusted into accurate operative relation. A contractile spring 15 75 is secured at one end to the wall 48 of the base body and is secured at its other end to the lever arm 72. This spring normally acts upon the lever 70 to hold the member 74 out of engagement with the thrust receiving member as best appears in 20 Fig. 1.

The lever 70 is operative against the action of the spring 75 by means such as a foot treadle (not shown) disposed beneath the head of the 25 machine as a whole. 76 indicates a link which is connected at its bottom end to said treadle. The top end of said link is connected to one arm 77 of a bell crank lever 78 that is pivoted at 79 to the bottom portion of the base 20. The other 30 arm 80 of said lever is connected to one end of a link 81, the other end of which has a pin and slot connection 82 with the bottom end of the lever arm 72. A contractile spring 83 is provided between the link 81 and bottom cover plate 29 of 35 the base to assist the spring 75 in functioning for the purpose described.

When the foot treadle before mentioned is depressed, it exerts a downward pull on the link 76 and this operates to impose an end thrust on the 40 link 81 in one direction (to the right as appears in Fig. 1). So soon as the play between the pin and slot connection 82 is taken up, the link 81 operates to swing the lever 80 counterclockwise to engage the thrust element 74 against the ball 45 61 to move the pulley 63 into driving relation with the balance wheel 60 so that the shaft 43 is driven from the pulley. When pressure on the before mentioned treadle is released, the springs 75 and 83 cooperate to swing the lever 70 in a 50 clockwise direction in Fig. 1. This removes the element 74 from the ball 61 when the spring 65 functions to move the pulley out of driving relation with respect to the balance wheel.

55 85 indicates a bar associated with the head 38 of the arm 21. This bar has sliding guided bearing in the top and bottom wall parts 86—87 of said head and carries a clamp 88 at its bottom end outside the head whereby one or more needles 89 may be operatively secured to the bar 60 85. In the head between the bar 85 and the boss 42 and operatively connected to the bar and to one end of the shaft 43 respectively is located mechanism indicated as a whole as at 91 (see Fig. 1) whereby the needle bar 85 is vertically 65 reciprocated from said shaft and whereby the usual thread take-up mechanism in the head (not shown) is also actuated. As the mechanism 91 is conventional in lock stitch sewing machines, it is not believed necessary to describe the various parts thereof in detail.

In the head 38 immediately behind the needle bar is located the usual presser foot bar. As the presser foot bar and associated presser foot and like parts form no particular part of the 75

present invention, the same is neither illustrated nor described herein.

The top wall 86 of the head 38 is made to provide an open top well 100 for holding a lubricating absorbing material such as cotton waste. A part of said well has its bottom 101 disposed at a higher elevation than the bottom of the remainder of said well and a vertical opening 102 is provided in the wall 86 between said bottom and the interior of said head 38. An absorbent wick 103 is disposed in said opening with its bottom end depending with a position to be engaged by a part of the mechanism 91 before mentioned, whereby said mechanism is lubricated. The right hand end of the well 100 is formed by a partition 104 that is lower in elevation than the bottom 101 before mentioned. This tends to produce a spillway. One end of a tube 105 having its major portion arranged in the arm 37 is secured in the partition to discharge into the well 100, the other end of said tube being connected to the outlet or discharge side 56 of the pump before mentioned in the base. A cover plate 106 is removably secured in the top surface of the wall 86 to close the well.

In the left hand end wall of the standard 36 of the arm 21 at the bottom thereof, is formed an open top pocket or well 107 (see Fig. 1). One end of a tube 108 arranged in the hollow base above the rock shaft 32 therein is fixed in the bottom of said pocket and the other end of the tube is arranged to discharge upon said shaft adjacent its bearing in the wall 24 of the extension 23.

A shuttle race body 130 is engaged in seats 25a-25a, provided therefor in the extensions 25-25 of the base. In the shuttle race body is located the usual shuttle body and associated mechanism, the shuttle body being operatively engaged by a driver 135 carried on the associated end of the shaft. The mechanism within the race body forms no particular part of the present invention and therefore need not be illustrated or described in detail herein because of the disclosure in our previously mentioned pending application.

When the sewing machine is in operation, the pump plunger 52 in its reciprocation in the cylinder 53 operates first to draw in a charge of oil from the hollow base 20 and force it up the tube 105 to discharge into the well 100. This keeps the waste therein well saturated with oil, the excess oil flowing over the partition 104 to drain back toward and into the hollow base. A part 55 of the oil in the waste in the well flows down the wick 103 so that in each cycle of operation of the mechanism 91 in the head, the wick is engaged to transfer oil to said mechanism for lubricating purposes. As the excess oil overflows the partition 104 and drains back toward the hollow base 20, a part thereof washes over the bearing 42 for the shaft 43 and the remainder flows along the bottom wall of the arm 37 and then down the left hand wall of the standard 38. A part of this oil drains back into the hollow base 20 and a part flows into the pocket 107 and down the tube 108 to discharge onto the

top side of the shaft 32 near its bearing in the wall 24 of the hollow extension 23. It is apparent that in the operation of the machine the arm 46 in its rocking movement will dip into the oil in the base 20 and produce a splash, a part of which will eventually lodge upon the connection for the rod 45 with the crank 44 as well as upon the bearings 40-41 for the main drive shaft 43. To facilitate supplying oil to the machine for replenishing purposes, the top wall of the arm 37 above and in line with the crank 44 is provided with a filler opening normally closed by a removable plug 21a. By reason of the use of the wick for supplying oil to the mechanism 91 in the head 38, there is no flooding or excess of oil at this locality so that oil cannot be thrown out through the usual slot in the head for the associated thread take up lever (not shown herein).

By reason of the construction described, all operating parts, except those of the shuttle are enclosed as a protection against wear, by reason of dust, lint and other foreign particles and lubrication of said parts is positive.

While in describing the invention we have referred in detail to the form, arrangement and construction of the various parts thereof, the same is to be considered only in the illustrative sense so that we do not wish to be limited thereto except as may be specifically set forth in the appended claim.

We claim as our invention:

A sewing machine embodying therein means providing a hollow base for containing a lubricant and a hollow overhanging arm thereon communicating at one end therewith and terminating at its other end in a hollow head, a main drive shaft in said arm, means providing a bearing in said head for one end of said shaft and which shaft has a portion disposed in said head, a needle carrying bar mounted in the head for a vertical reciprocating movement, means in said head actuated from the main drive shaft for reciprocating said bar, a second shaft in said base, means providing longitudinally spaced bearings in said base for said second shaft, means at one end of said base and driven from said second shaft for coacting with the needle in forming stitches, means for delivering lubricant from said base to a well in the top portion of said head, said well being positioned above the bearing means for said main drive shaft, means for delivering lubricant from said well to said means in said head for reciprocating said needle bar, said well having a spillway in the interior of said hollow arm, said bearing means for said drive shaft being disposed below said spillway and in the path of the overflow so as to be lubricated from said overflow whereby the lubricant flowing from said spillway is conducted by means of gravity along the lower interior wall of said hollow arm to said base, and means in said base for receiving the lubricant from said hollow arm and delivering the lubricant to at least one of said bearings for said second shaft.

NATHAN WALDMAN.
